UNITED STATES PATENT OFFICE

100,694

DESIGN FOR A DISPLAY STAND

Hans A. Hansen and Solomon R. Salkin,
Peoria, Ill.

Application May 20, 1936, Serial No. 62,745

Term of patent 7 years

To all whom it may concern:

Be it known that we, Hans A. Hansen and Solomon R. Salkin, citizens of the United States, residing at Peoria, in the county of Peoria and State of Illinois, have invented a new, original, and ornamental Design for a Display Stand, of which the following is a specification, reference being had to the accompanying drawing, forming part thereof.

The figure is a perspective view of a display stand, showing our new design.

We claim:—

The ornamental design for a display stand as shown.

HANS A. HANSEN.
SOL. R. SALKIN.
